[57] CLAIM

The ornamental design for goggles, as shown and described.

DESCRIPTION

FIG. 1 is a front elevational view of the goggles embodying my new design;

FIG. 2 is a top plan view thereof;

FIG. 3 is a bottom plan view thereof;

FIG. 4 is a rear elevational view thereof; and

FIG. 5 is a side elevational view, the opposite side being a mirror image thereof.

The flexible head band disclosed by means of broken lines in FIGS. 2, 3 and 5 has been shown for illustrative purposes only.

FIG. 1

FIG. 2

FIG. 3

FIG. 4
